UNITED STATES PATENT OFFICE.

GRATTON S. REYNOLDS, OF TARENTUM, PENNSYLVANIA.

POWER-TRANSMITTING MECHANISM.

Application filed August 10, 1922. Serial No. 580,998.

To all whom it may concern:

Be it known that I, GRATTON S. REYNOLDS, a citizen of the United States, residing at Tarentum, in the county of Allegheny and State of Pennsylvania, have invented a certain new and useful Improvement in Power-Transmitting Mechanism, of which the following is a specification.

This invention is for a power transmitting mechanism, and relates to a device for imparting an intermittent movement to a driven shaft from a continuously rotating driving shaft.

Devices of this kind are adapted for a wide range of machines, particularly those machines having a feeding mechanism associated therewith, where the feeding device is driven from the machine, and the device is used in transferring proper motion to the feeding device from the machine. An example, for instance, is a crushing mill having an automatic conveyor for supplying material thereto in proper amount relatively to the capacity of the crusher, the invention being utilized to give the desired ratio of movement between a driven shaft and a driving shaft for the conveyor.

The primary object of my invention is to provide an intermittent feed of this kind of extremely simple construction, which is positive in its operation and which is strong and durable. Other important objects are to provide means for regulating or varying the distance the driven shaft is rotated and for providing a safety device including a yieldable means for preventing damage to parts in the event of the driven shaft becoming jammed, for any reason.

The invention may be readily understood by reference to the accompanying drawings, in which:

Fig. 1 is a side elevation of the device, showing the parts in operating position;

Fig. 2 is an end view of Fig. 1, with part of the device shown in section;

Fig. 3 is a detail view showing a plan view of a crank on the driving shaft;

Fig. 4 is a view similar to Fig. 1, showing the parts in inoperative position;

Fig. 5 is an end view of the mechanism, as shown in Fig. 4; and

Fig. 6 is a front view of the crank.

In the drawings, 5 indicates a driving shaft which is coupled with any suitable machine, not shown, and which, in most in-

stances, operates at a relatively high speed. On the end is a crank and cam structure, preferably comprising an integral casting 6 having a hub 7 on which is formed a cam 8 and a circular portion 9 having a radial arm 10 formed thereon. The arm 10 has a T-slot 11 therein, extending from its outer end inwardly toward the center. At each side of this slot, are corrugations or teeth 12.

Having its head in the T-slot, is a bolt 13 which is eccentric to the shaft and which may be moved toward or away from the center in the T-slot. Surrounding the shank of this bolt is a sleeve 14 having a head portion 15 in which are teeth adapted to mesh with teeth 12 on the crank. This sleeve is held in position by nut 16 and washer 17 on the end of the projecting outer end of the bolt. By means of the toothed head 15 on sleeve 14 cooperating with the teeth 12, the bolt may be adjustably clamped the desired distance from the center of the shaft 5.

Journalled about the sleeve 14 is the end portion 18 of a connecting link 19. The connecting link 19 has a removable head 20 secured thereon. Slidable on the link, below the head, is an exteriorly threaded nut 21, and interposed between the nut and the head is a compression spring 22. The upper end of the link is slidably retained in a cylinder 23, into the bottom or outer end of which is screwed the nut 21, to hold spring 22 in place, preferably under some compression. Normally, the head 20 of the link abuts against the end of the cylinder 23, or an abutment therein, as shown in Fig. 2.

Extending upwardly from the other end of the cylinder is a rod portion 24 having an eye 25 on its upper end.

The driven shaft is designated 26. Keyed thereto is a wheel 27 having an annularly toothed face 28, the teeth of which are preferably relatively open or far apart and have straight vertical faces on one side 100 thereof and inclined faces on the other, the tops of the teeth preferably being flat.

Loose on the shaft 26 and slidable longitudinally thereon is a second clutch member or wheel 30 having a relatively long hub 31 105 and a disk portion 32 having teeth 32^a on the face thereof which is opposite wheel 27. These teeth are shaped similarly to those of wheel 27, and are adapted to cooperate therewith. On that face of the disk which 110

is not toothed is an ear 33 and on the periphery of the disk is a lug 34. A bolt 35 passing through ear 33 and lug 34 is also passed through eye 25 on rod 24, whereby the cylinder is connected with the disk.

Abutting against the end of hub 31 is a compression spring 36, held in compression by a collar 37 fixed against longitudinal movement on the shaft. This spring urges the wheel 30 into engagement with wheel 27.

Pivoted between its ends to a fixed bracket 40, by means of bolt 40^a passing through it, is a lever 41 having a feather or separable collar 42 at its upper end engaging an annular groove in the hub 31 of wheel 30. The lower end of the lever is provided with a suitable cam engaging means, such as a roller 43, which is disposed in the annular space between cam 8 and disk 9 of member 6.

In operation, shaft 5 is continuously rotated. Due to the crank pin provided by the bolt and sleeve construction being eccentric, a reciprocable movement is imparted to link 19. This movement is transmitted when the link 19 moves downwardly through spring 22 to cylinder 23, the spring being sufficiently stiff to resist yielding under normal conditions. Upward movement of link 19 raises cylinder 23 by reason of the head 20 abutting against the end wall of the cylinder. Link 19, cylinder 23, and rod 24 thus normally provide a connecting link between the crank pin and bolt 35. Therefore, as the link connection reciprocates, wheel 30 is oscillated about shaft 26.

The cam 8 is so arranged that when the crank pin starts on its downward movement, the recessed part of the cam comes opposite roller 43 on the end of lever 41. This allows spring 36 to force wheel 30 toward wheel 27, moving their teeth into cooperative engagement, as shown in Fig. 1. Then, as rod 24 is pulled downwardly, wheel 30 rotates wheel 27 in a corresponding direction. Just after the crank pin reaches its lowermost position, cam 8, engaging roller 43, rocks the lever on its pivot 41 in a direction to withdraw wheel 30 through feather 42 from operative engagement with wheel 27 and against the action of spring 36. The parts are then in the position shown in Fig. 4, in which position they remain until the crank pin begins its next downward arc of movement. Thus, while shaft 5 continuously rotates, and wheel 30 is continuously oscillated, the wheel 27 and consequently the shaft 26, is moved in one direction only, and only through a limited arc at each successive movement.

By suitable adjustment of the crank pin toward or away from the center of the shaft, the movement of the shaft 26 with each rotation of shaft 5 may be varied. The teeth 12 on the crank preferably bear a certain known relation to the teeth on the wheels 27

and 30, so that the teeth of these two wheels will always move into mesh at the proper time.

If, for any reason, the resistance offered to the rotation of shaft 26 exceeds a predetermined maximum, the spring 22 will yield, allowing a relative movement between link 19 and cylinder 23. This will allow the shaft 5 to continue to rotate without being subjected to damaging strains in the event of the load on shaft 26 becoming too great, or in the event of shaft 26 becoming jammed.

In order to provide a manual control, which will enable shaft 5 to rotate without driving shaft 26, I provide a hand lever 45 pivoted on bolt 40^a and having an angular arm 46 thereon in which is a laterally projecting pin 47. When lever 45 is pulled down, pin 47 is swung through an arc, contacting with lever 41 above its pivot point, thereby holding wheel 30 out of operative position against the compression of spring 36.

By referring to Figs. 1 and 4, it may be seen that the sleeve 14 of the crank pin construction is of sufficient length to enable end portion 18 of link 19 to slide therealong with the sliding movement of wheel 30.

With the parts arranged as shown in the drawings, shafts 5 and 26 are rotated in the same direction. By reversing the wheels on the shaft 26, that shaft may be driven in a reverse direction.

Various changes may be made in the detailed construction and arrangement of parts within the contemplation of my invention, and within the scope of the appended claims.

What I claim is:

1. A power transmission device comprising a driving shaft, a driven shaft, a pair of wheels on the driven shaft having their opposed faces provided with interfitting teeth, one of said wheels being free on the shaft and the other wheel being keyed thereto, one of said wheels being reciprocable on the shaft into and out of operative engagement with the other, means for imparting an oscillatory movement from said driving shaft to said free wheel, and means operated by means on the driving shaft for effecting the reciprocation of said reciprocable wheel, whereby said wheels are in operative engagement during a portion only of the oscillatory travel of said free wheel.

2. A power transmission device comprising a driving shaft, a driven shaft, a clutch on said driven shaft reciprocable longitudinally of the shaft into and out of operative position, a crank on the driving shaft, means for connecting the crank and clutch member for imparting an oscillating movement thereto, means driven from the driving shaft for reciprocating said clutch member whereby it will be in operative position

throughout a portion only of its oscillatory travel, and adjustable means for varying the oscillatory movement of said clutch member to vary the rotative movement imparted to 5 the driven shaft with each cycle of oscillation of the clutch member.

3. A power transmission device including a driving shaft, a driven shaft, cooperating wheels on said driven shaft, one of which is 10 movable longitudinally into and out of engagement with the other, one of said wheels being keyed to the shaft and the other one being free thereon, a crank on the driving shaft, means connecting the crank and the 15 free wheel on the driven shaft, whereby an oscillatory motion is imparted to said wheel upon rotation of the driving shaft, a cam on the driving shaft, a lever reciprocated by the rotation of said cam, and means on said 20 lever for effecting a reciprocable movement of the longitudinal movable wheel, whereby said wheels are in cooperative relation during a portion only of the oscillatory movement of the free wheel.
- 25 4. A power transmission device including a driving shaft, a driven shaft, cooperating wheels on said driven shaft, one of which is movable longitudinally into and out of engagement with the other, one of said wheels being keyed to the shaft and the other one being free thereon, a crank on the driving shaft, means connecting the crank and the 30 free wheel on the driven shaft, whereby an oscillatory motion is imparted to said wheel upon rotation of the driving shaft, a cam on the driving shaft, a lever reciprocated by the rotation of said cam, and means on said 35 lever for effecting a reciprocable movement of the longitudinal movable wheel, whereby said wheels are in cooperative relation during a portion only of the oscillatory movement of the free wheel, said connecting means including a yieldable connection arranged to yield when the wheels are in cooperative relation when the driven shaft encounters a predetermined maximum resistance against rotation.

the rotation of said cam, means on said lever for effecting a reciprocable movement of the longitudinal movable wheel, whereby said wheels are in cooperative relation during a portion only of the oscillatory movement of the free wheel, and a manually operable means for holding said lever against operation with the two wheels out of cooperative engagement. 40

5. A power transmission device including a driving shaft, a driven shaft, cooperating wheels on said driven shaft, one of which is movable longitudinally into and out of engagement with the other, one of said wheels being keyed to the shaft and the other one being free thereon, a crank on the driving shaft, means connecting the crank and the free wheel on the driven shaft, whereby an oscillatory motion is imparted to said wheel 55 upon rotation of the driving shaft, a cam on the driving shaft, a lever reciprocated by the rotation of said cam, and means on said lever for effecting a reciprocable movement of the longitudinal movable wheel, whereby 60 said wheels are in cooperative relation during a portion only of the oscillatory movement of the free wheel, said connecting means including a yieldable connection arranged to yield when the wheels are in cooperative relation when the driven shaft encounters a predetermined maximum resistance against rotation. 65

In testimony whereof I hereunto affix my signature.

GRATTON S. REYNOLDS.
